CLAIM

The ornamental design for a jewelry item, as shown and described.

DESCRIPTION

FIG. 1 is a front perspective view of a jewelry item showing my new design;

FIG. 2 is a front view of the jewelry item shown in FIG. 1; FIG. 3 is a rear view of the jewelry item shown in FIG. 1; FIG. 4 is a left side view of the jewelry item shown in FIG. 1;

FIG. 5 is a right side view of the jewelry item shown in FIG. 1;

FIG. 6 is a top view of the jewelry item shown in FIG. 1; FIG. 7 is a bottom view of the jewelry item shown in FIG. 1;

FIG. 8 is a front perspective view of a second embodiment of a jewelry item showing my new design;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken lines depicting a hinge in FIGS. 8-14 represent unclaimed portions of the jewelry item.

1 Claim, 6 Drawing Sheets
